UNITED STATES PATENT OFFICE.

JAMES H. MUNRO, OF NEWARK, NEW JERSEY, ASSIGNOR OF ONE-HALF TO JOHN MILTON VAN ORDEN, OF NEWARK, NEW JERSEY.

COVERING FOR ROOFS AND THE LIKE.

967,542.

Specification of Letters Patent. Patented Aug. 16, 1910.

Application filed January 2, 1909. Serial No. 470,387.

To all whom it may concern:

Be it known that I, JAMES H. MUNRO, of Newark, New Jersey, have invented certain Improvements in Coverings for Roofs and 5 the Like, of which the following description, in connection with the accompanying drawings, is a specification, like letters on the drawings designating like parts.

This invention relates to coverings for 10 roofs and the like, and is of special utility when embodied in the construction of roofing units possessing some of the properties of roofing tiles, as for example the ease with which they may be handled and their 15 durability, but of much less weight, less expense of manufacture and laying, less fragile, and more capable of conformation to the contour of the roof on which my improved units are to be used, it being understood that I contemplate their utilization in 20 any field for which they are adapted by their nature.

An important object of my invention is to provide a roofing unit somewhat comparable in constitution and cost of manufacture with the type of roofing known as "slag roofs" and "gravel roofs", but more permanent, more uniform in structure, and more pleasing in appearance, so that they 30 may be substituted with benefit on roofs where at the present day the cheapness of the slag or gravel roofs constitutes a reason for their installation in spite of their relative lack of permanence and unsightly appearance after their decadence begins.

Another important object of my invention is to provide a roofing unit of substantial thickness which may be more readily bent than a certain well-known type or tile which 40 may be described briefly as an agglomerate of asphalt, usually the common discarded asphalt from worn-out streets, or waste asphalt, with grit of some sort, compressed under blocks and laid in abutting relation, 45 but lacking in flexibility so far as the individual units are concerned.

In the construction of slag roofs and gravel roofs at the present day, large areas of roof are covered with pitch or asphalt in 50 a relatively thick layer and thereafter sowed or sprinkled with granular material such as slag, gravel or the like, the binder or foundation being as a rule of a low-melting pitch which under the influence of different 55 temperatures runs, cracks, and loses its grip

upon the granular surface material, so that deprived of this protection the pitch weathers badly, runs and otherwise loses its integrity and quality as a water-proofing.

To accomplish my object of providing a 60 cheap, efficient and permanent substitute for slag roofs and inflexible tiles, I prefer to utilize similar materials to those used in the construction of these earlier roof-coverings, and accordingly I prefer to assemble in a suitable holder a quantity of granular or gritty material such as gravel, slag, broken stone, slate or brick or other mineral substance, to a thickness not differing greatly under ordinary circumstances from that of inflexible 65 or other tiles for roofing purposes, and of a size similar to the stock sizes of roofing tiles, although I contemplate under favorable circumstances using a somewhat larger unit of tile to facilitate speedy covering of a given 70 area of roof and also to lessen the cost of manufacturing. The granular material having thus been assembled, I apply thereto a suitable binder in quantities sufficient to unite the component granules permanently 75 and to render the unit substantially impervious to moisture preferably, although where laid upon a suitable water-proof foundation, this impervious quality is not so important as the capability of the unit for wear; and 80 I prefer also that the binding action shall be of such a character as to permit some degree of flexibility in the individual tile units, this not being absolutely essential to my invention in its broadest form.

In certain situations, as in gutters and other curved surfaces commonly found on roofs, and on structural parts such as ridges, posts and towers, balconies and store fronts 95 or bay windows, a very considerable degree of flexibility in the individual tiles will permit their use in a much wider variety of situations than at the present day, and to permit such adaptation, I provide a high degree of flexibility and expansibility by interrupting the surface of the tile in one or more regions, as for example by scoring the surface and sometimes by dividing it into a plurality of subsidiary parts, which may be connected by suitable backing of flexible 100 material to form a unit which can be laid as a whole, in abutting relation with similar units.

The various features of my invention will be illustrated and described fully in the ac- 110

companying drawings and specifications and pointed out in claims.

In the drawings:—Figures 1 and 2 are views in vertical section of a unit for roofing, embodying my invention, and shown in course of manufacture: Fig. 3 shows the completed unit in perspective: Figs. 4 and 5 are views similar to Figs. 1 and 2 of modified forms of unit in course of manufacture:

- 10 Fig. 6 is a plan view of a roofing unit scored to promote conformation to irregular surfaces, in accordance with my invention; and Fig. 7 is a fragmentary view in vertical section of the same, on the line 7—7, Fig. 6: 15 Fig. 8 is a view similar to Fig. 7 of a modified form of scored unit: Figs. 9 and 10 are views on a smaller scale, similar to Fig. 7, showing the scored unit in convex and concave curves: Fig. 11 shows in section a unit 20 similar to that of Fig. 7, provided with a backing, and fractured along the scored lines; and Figs. 12, 13 and 14 show a modified backing.

In the embodiment of my invention selected for illustration and description to enable ready and complete understanding of my improvements, and referring first to Figs. 1 to 5, the reference numeral 1 designates an aggregation of granules or pieces 25 of material, such as gravel, slag, grit, broken stone, brick or mineral, introduced temporarily within a suitable frame or holder 2 of wood or metal or other suitable material which for the sake of convenience may be 30 placed upon a backing 3 resting upon a suitable supporting surface 4, preferably level, in instances where the unit to be formed is for the purpose of a roofing unit. I then, in accordance with my invention, apply a 35 suitable binder, which may be of any suitable material, but which will preferably be of a material or substance having a high melting point so as not to be affected by heat in summer or at low latitudes, and which 40 is also preferably highly tenacious, somewhat elastic, and impervious to moisture, a suitable substance for this purpose being asphaltum with but a slight admixture of sand or pulverized grit, the latter only being 45 used where it is found that that binder lacks consistency, and being dispensable in many instances. In Figs. 2 and 3 this binder is indicated by the dark material 5 in the interstices between the granules 1, Fig. 2 showing 50 the unit before removal from the frame and backing, while Fig. 3 shows the unit in its manufactured form ready for laying in abutting relation with similar units, directly upon the roof in place of the slag or gravel 55 of the roofs at present in general use.

When the backer 3 is to be removed it may be treated if found desirable with grease or oil to prevent adhesion of the binding material, but if desired the backing 60 may be allowed to remain as a unitary

part of the tile, and in that event I may apply a somewhat greater proportion of binding material relatively to the space occupied by the granules, especially in the stratum 6 shown in Fig. 4 intervening between the unit proper 7 and the flexible backing of roof paper, cloth or other suitable material 8.

Where a neater finish is desired on the top and bottom I may form strata (as shown in Fig. 5, for example) of binding material, 9 and 10, and the backer 11 is shown at the top in this instance, where it remains connected with the unit 12 after the holder 13 has been reversed, the temporary false backing 14 removed, and the unit cleared from the holder.

I have shown in Fig. 6 and Fig. 7 a unit formed of asphaltum or other suitable material as the principal ingredient, with such grit, granules or other particles as may be desired to give the same consistency, the latter being disregarded in these figures, which are intended to illustrate the scoring by which additional flexibility is imparted to the unit, the composition of this unit being considered for the sake of illustration as similar to that of an inflexible tile. Expansibility is also served by scoring.

In accordance with my invention the material of the unit is scored at 15, dividing the same into a considerable number of subsidiary unit portions 16, the scoring being shown as extending substantially through the thickness of the unit, and Figs. 9 and 10 show on a smaller scale the manner in which a unit thus formed may be flexed to present a convex or concave surface.

In Fig. 8 the scorings 17 do not extend so deeply into the material of the unit 18, and if the material thereof be not sufficiently flexible, I contemplate the possibility of a fracture occurring along the lines of the scorings when the unit is bent. Proper water-proofing upon the underlying roof will 110 render such fractures negligible.

In Fig. 11 I have shown a unit 19 scored at 20 and provided with a backing 21 secured by a layer 22 of cement, the unit being shown as applied to a curved surface and showing fractures 23 where the unit has been bent.

In the modification shown in Figs. 12, 13 and 14, the backing of the units takes the form of shingles 24, to the exposed portions 25 of which a composition 26 of grit and binder has been applied, preferably before the shingles are laid, and preferably extending over the edges of the individual shingles.

Having described my invention thus fully and suitable means for carrying same into effect, it will be understood that I do not limit myself to the particular construction illustrated and described nor to the specific materials cited nor in general other- 130

wise than as set forth in the claims read in connection with this specification.

What I claim and desire to secure by Letters Patent is:—

- 5 1. A unit for coverings for roofs and the like; comprising an extended surface of weather resisting material weakened at intervals to permit fracture in conforming to the surface to be covered, and having a 10 backing to which said surface material is secured by a stratum of flexible cement; substantially as described.
- 15 2. A tile for roofs and the like; said tile consisting of a wear-resisting layer of granular material frangible at intervals bound by tenacious material, such as asphalt, and a backing of fibrous material; substantially as described.
- 20 3. A tile of frangible material presenting a hard wearing surface and comprising also binding or holding material to allow for fracture or breakage without separation; substantially as described.

4. A tile of the class described; being weakened at intervals to permit fracture of 25 said tile to conform to the surface to be covered; said tile being provided with binding material to close said fractured regions; substantially as described.

5. A tile of the class described; being 30 weakened at intervals to permit fracture of said tile to conform to the surface to be covered; said tile being composed of a homogeneous composition presenting a wear-resisting and weather-resisting surface and having 35 as an ingredient a binding material such as bitumen to close said fractured regions under the application of heat subsequently to said fracture.

Signed at Newark, in the county of Essex 40 and State of New Jersey, this 31st day of December, 1908.

JAMES H. MUNRO.
